UNITED STATES PATENT OFFICE.

ALBERT W. FRANKLIN, OF NEW YORK, N. Y., ASSIGNOR TO CHAS. FRESHMAN CO. INC.,
OF NEW YORK, N. Y., A CORPORATION OF NEW YORK.

VARIABLE-CONDENSER DRIVE.

Application filed October 23, 1925. Serial No. 64,312.

This invention relates to improvements in devices used to impart rotary motion to the rotor plates of condensers as used in radio and like apparatus.

5 In order to obtain the best results from such apparatus, as in tuning in, a smooth motion is desirable and preferably also a slow positive movement under the instant control of an operator.

10 Knob actuated, direct connected dials, while convenient and common in use, are regarded in the present state of the art, as archaic, a too rapid movement being ineffective in securing the degree of accuracy 15 demanded in securing efficient manipulation of the apparatus.

It is therefore one of the objects of the present invention to provide a device, using the customary knob and a calibrated dial, 20 but so arranged that the speed of the dial is greatly reduced in relation to that of the knob, assuring a fineness of dial setting that is highly desirable.

A further feature is in the provision of 25 means for rotating a dial with the utmost nicety and precision, and also with absolute positiveness not attainable with friction types of drives.

Another aim is to produce a simple mechanical device for the purpose mentioned, 30 that is inexpensive to construct and install, is of pleasing appearance, and as easy to operate as any knob controlled condenser of common type.

35 These several objects are achieved by the characteristic features of the present invention as hereinafter described, and illustrated in the associated drawing, forming an essential part of this disclosure, and in which:—

40 Fig. 1 is a front elevational view of an embodiment of the invention illustrating its application to a conventional type of condenser.

Fig. 2 is a side elevational view of the 45 same, showing a fragmentary portion of a condenser, a part of the dial and supporting panel being in section.

In this drawing the numeral 5 is used to 50 designate a panel, forming the front wall of the usual cabinet, and extending at a right angle rearwardly from the panel is a support plate 6 carrying a frame 7 in which the condenser is mounted at a spaced distance from the panel.

55 The condenser, which may be of any ap-

proved type, consists of stator plates, generally designated by the numeral 8 and rotor plates 9, the latter being fixed on a spindle 10 in the usual manner. It is to be noted however that the spindle does not project 60 through the panel 5.

Formed through the panel is a segmental cut out or window 11 preferably having bevelled edges, this window registering with the graduations 12 on a dial 13, the latter 65 having a hub 14, fixed rigidly on the end of the spindle 10.

Said dial is circular in profile and contains a segmental opening 15 concentric with its periphery and extending in length 70 substantially one-half the circumference of the dial.

The outer edge of the opening 15 is provided nearly its full length with teeth 16, constituting in effect an internal segmental 75 gear, meshing with which is a pinion 17 fixed on a stub shaft 18, the outer end of which passes freely through an appropriate opening 19 in the panel 5.

The inner portion of the stub shaft 18 is 80 reduced in diameter, as at 20, and is journaled to rotate in the arms 21, 22 of an inverted U-shaped bracket 23, the inner arm 22 of which is provided with an elongated foot 24, secured to the upright frame 7 by 85 screws or other fastening means 25.

On the outer end of the stub shaft 18 is fixed a knob 26 of any type convenient for ready twirling, and whereby the pinion is 90 revolved to transmit motion directly to the dial 13, but obviously at a greatly reduced speed permitting a fine and accurate adjustment.

It will be noted that no extra gears are 95 used, the dial itself being pierced and one edge of the material defining the piercing provided with teeth for cooperative engagement with a single pinion on the knob shaft which pinion projects through the piercing in the dial.

From the foregoing it will be seen that a simple device for this purpose has been disclosed in the preferred form of its embodiment, but it is not desired to restrict the details to the exact construction shown, it 105 being obvious that changes, not involving the exercise of invention, may be made without conflicting with the scope of the appended claims.

Having thus described my invention, what 110

I claim as new and desire to secure by Letters Patent, is:—

1. A radio condenser drive comprising in combination with a variable condenser, a dial fixed on the condenser spindle, said dial having a concentric opening provided with teeth on the outer edge, a bracket fixed on the condenser frame, a stub shaft rotatable in the bracket, a pinion fixed on said shaft 10 to engage said teeth, and a knob to rotate said shaft.

2. A radio condenser drive comprising in combination with a variable condenser, a dial fixed on the condenser spindle, said dial having a scale on its face extending over half its circumference near the edge, an internal segmental gear integrally formed in the portion of said dial opposite the scale, a pinion meshing with said gear, a shaft on 20 which said pinion is fixed, said shaft being

carried by the condenser frame, and means for twirling said shaft.

3. A radio condenser drive comprising in combination with a variable condenser, a cabinet and a panel at the front thereof, 25 said panel having a window, a dial fixed on the rotor spindle of said condenser to expose its scale through said window, an internal segmental gear formed in said dial, a shaft carried pinion engaging said gear, 30 an inverted U-shaped bracket fixed on the frame of said condenser in which said pinion shaft is mounted, said shaft extending through the panel, and a knob on said shaft to directly transmit rotation to said dial.

Signed at New York, in the county of New York, and State of New York, this 23 day of September, 1925.

ALBERT W. FRANKLIN.
